UNITED STATES PATENT OFFICE.

GORDON P. GAVIN, OF CHICAGO, ILLINOIS.

PROCESS OF CONSTRUCTING CLOSET-BOWLS.

1,289,151.

Specification of Letters Patent. Patented Dec. 31, 1918.

Application filed March 11, 1915. Serial No. 13,778.

To all whom it may concern:

Be it known that I, GORDON P. GAVIN, a citizen of the United States, residing in Chicago, in the county of Cook and State 5 of Illinois, have invented a new and useful Improvement in Processes of Constructing Closet-Bowls, of which the following is a specification.

My invention relates in general to the ceramic art and has more particular reference 10 to the casting of ceramic articles having tortuous passageways or revolute surfaces or both such as closet bowls and the like. Although the invention hereinafter disclosed 15 is described for the purposes of illustration in connection with a closet bowl, it will be manifest that it has a much wider and more general application, being capable of effective use in the construction of many other 20 ceramic articles of irregular and non-symmetrical contour or having internal tortuous passageways.

Prior to my invention it has been the custom to form ceramic articles of irregular 25 formation through the use of molds in a variety of ways, two of which may be cited as examples. Parts have been first cast and partially dried, the molds forming them removed and other parts subsequently cast 30 thereto by the positioning of other molds. In some instances toilet seats and the like have been constructed by casting the body of the bowl and successively casting thereupon other parts determined by the curves 35 of the article in forming the tortuous passage required. This form has required considerable time as each part must be dried before the next may be added and its use has been accompanied with considerable loss 40 by reason of the uneven drying and consequent uneven shrinkage of the parts before and during baking, which frequently causes the article to crack.

Another process employed has been that 45 of providing a two-part vertically separable mold for determining the outer contour and for determining certain members of the inner portions. In this last mentioned arrangement, however, the molds have been 50 poured full of ceramic materials in semi-liquid state, the material of the mold absorbing sufficient moisture to produce the desired depth of incrustation, the remainder of the material thereafter being poured out

and the shell thus left permitted to dry. It 55 is manifest that this arrangement does not take care of the tortuous siphon passageway, a permanent core being required for this purpose. It, moreover, produces an article of different texture at and near the surface adjacent the mold from that at or near 60 the surface remote from the mold. This procedure has also resulted in the loss of considerable ceramic or article forming materials by reason of the fact that the substance 65 poured off or removed after incrustation, is not available for subsequent use with good results. The drying is also somewhat uneven where the last described procedure is used. This procedure when closet 70 bowls are made also requires the provision of a permanent core which cannot be removed, this core adding materially to the weight and expense of construction.

It is a principal object of this invention to 75 improve the art of making ceramic articles, to eliminate these and other disadvantages, that is, to provide a method or process of constructing a closet bowl or other ceramic article, all parts of which will have even 80 and uniform texture, the construction of the bowl permitting all parts to be simultaneously constructed and simultaneously manipulated to produce even drying, thereby minimizing the danger of cracking in bak- 85 ing.

A further object of the invention is the provision of a process which will reduce materially the time and labor required in the construction of articles of the character described. 90

Another object of the invention is the provision of a process for making ceramic articles which may be practised by the ordinary workman without special education in 95 the working of pottery, the invention being capable of use without the exercise of nicety of judgment and without the use of peculiar manual skill.

A still further object of the invention is 100 the provision of a process of constructing closet bowls and the like which will permit the use of heavier "slip", that is ceramic materials containing a smaller percentage of water, thereby giving to the bowl a tougher, 105 stronger texture and reducing materially the amount of water necessary to be taken up by the molds in casting.

A further object of the invention is the provision of a process which will insure the formation of articles of even thickness.

Other objects and advantages of the invention will be apparent as it is better understood from the following description when considered in connection with the accompanying drawing illustrating a preferred embodiment thereof.

10 On the drawings,

Figure 1 is a rear view of a closet bowl constructed in accordance with my present invention;

15 Fig. 2 is a section of a mold for the base or lowermost part of the bowl shown in Fig. 1;

Fig. 3 is a section through the molds used to form the part immediately above the base;

20 Fig. 4 is a similar view through the part next above;

Fig. 5 is a top plan view of the molds shown in Fig. 4;

25 Fig. 6 is a section through the trap spoon mold;

Fig. 7 is a section through one form of rim forming mold;

30 Figs. 8 and 9 are companion molds for forming the rim in slightly different manner;

Fig. 10 is a section through a part of a rim formed by the molds 8 and 9; and

Fig. 11 is a section through the assembled mold.

35 For the purpose of illustrating my invention I have shown it on the drawings as applied to the construction of a closet bowl. The invention contemplates the simultaneous casting in suitable molds of all of the parts of the bowl, the molds being so constructed and arranged that all parts are formed between surface determining faces of the molds, as will be later described.

40 Referring to Fig. 11 it will be noted that the closet bowl A in the present instance is divided into sections as follows: a base B, a body member C, a trap D, a bowl E and a rim F, the rim F being preferably of two parts G and H (see Fig. 10). The base B is formed by 45 the mold shown in Fig. 2, which mold consists in an upper half 15 and a lower half 16 having an internal casting space 17 of thickness and configuration desired in the finished base. Through the upper half 15 of 50 this mold a plug 18 is positioned for forming the waste passage 19. This plug is readily removable after the part has been cast. A supply hole 21 suitably located is provided and this supply hole is preferably 55 lined with brass or other material 22 to prevent clogging. The parts 15 and 16 and all of the parts to be hereinafter described are 60 preferably constructed of plaster of Paris or other suitable absorbent material. The body 65 forming mold shown in Fig. 3 consists of

four parts, which comprise a base 23, separable vertical halves 24 and an internal upwardly removable filler or core 25. A supply hole 26 like the supply hole 21 of the mold for the base is provided. The bottom 70 and top portions 23 and 25 extend in proper relation to form the thin shell 27. The down passage 28 from the trap is formed by a plug 29 seated at 31 in the bottom or base 23. The plugs 18 and 29 are preferably also 75 of absorbent material.

The bowl mold is shown in Figs. 4 and 5. This mold consists of a base 32, a top portion 33 and side portions 34, the parts being arranged to give the desired configuration and 80 thickness to the bowl part E. The trap forming spoon D is molded as shown in Fig. 6 between an upper half 35 and a lower half 36, a suitable pouring hole 37 being provided. On the drawings two ways of constructing the rim are disclosed. One, that shown in Figs. 8 and 9, causing the rim to be cast in two sections, and the other that shown in Fig. 7, causing it to be cast in a single piece, that shown in Figs. 8 and 9, 90 however, being preferred by me at this time. Under this arrangement the upper section G is cast between upper and lower molds 38 and 39 and the lower half, that shown in Fig. 9, between the upper and lower molds 95 41 and 42, suitable pouring holes 43, being provided. The mold shown in Fig. 7 is inverted in the figure and consists of a lower half 44 and an upper half 45. The supply connection is provided by the use of a plug 100 46 at the rear. A pouring hole 47 is of course provided.

Suitable air vents 50 are provided as indicated on the drawings.

When a closet bowl or other article made 105 in accordance with my invention is to be constructed, the molds shown in Figs. 2, 3, 4, 6 and preferably also in Figs. 8 and 9 are set up and a heavy slip poured into them until the incrustation fills the space permitted by the molds. The pouring of these molds is substantially simultaneous so that all of the parts start drying at the same time. After they have dried somewhat the base B is removed from its mold and positioned upon a support 51, like the part 16 of the base mold but of appropriate dimensions to permit shrinking of the base. Then the upper and lower parts 23 and 25 of the mold for the body C together with the 110 plug 29 are removed and the body still within the side molds is placed upon the base 51. Next the trap spoon D is removed from its mold and positioned as shown in Fig. 11. Thereafter the bowl E is positioned by removing the upper and lower parts 32 and 33 and placing it with the vertical side parts 34 of the mold upon the body and its embracing mold parts, as indicated in Fig. 11. The rim parts G and H, if the molds shown 115 120 125 130

in Figs. 8 and 9 are used are then removed from their molds, placed together as shown in Fig. 10 and positioned upon the top edge 52 of the bowl E. If the form of the mold 5 shown in Fig. 7 is used to construct the rim, this form is set up with the forms for the other portions and a similar slip is poured therein and emptied out after desired 10 incrustation by inverting the mold to the position shown in Fig. 7. This operation should be timed so that when the other parts of the mold are ready for assembling, this rim may also be positioned. This means that it may be cast substantially with the other 15 parts. As each cast section is positioned its faces and the faces of the part upon which it is received which become adjacent are roughened and a small amount of heavy slip or clay is inserted between them to form a bond. The parts thus assembled are permitted to dry and later baked in the usual 20 manner.

The rim section, when formed in two pieces permits the punching of the holes 53 provided for flushing from the inside of the lower section outwardly. This is extremely desirable, for if the form used in Fig. 7 is employed, the inside being more moist than the outside may permit slip to run down 30 into the holes after being punched and interfere with their perfect formation and free flow. The use of the embodiment shown in Figs. 8 and 9 also permits the truing up of the interior of the rim before 35 the parts of the rim are assembled as well as giving an equal consistency to the external and internal faces. It will be manifest from the foregoing that the thickness of all parts of the closet bowl are of predetermined 40 dimensions and the faces produced accurate. As all the parts dry simultaneously the length of time required to form a closet bowl is materially reduced and the danger of cracking or breaking in drying and baking 45 is minimized.

Where the process of making toilet bowls and other articles embodying my invention is utilized the molds themselves are not required to absorb undue amounts of water 50 and may be used repeatedly without heat drying.

It is thought that the invention and many of its attendant advantages will be understood from the foregoing description, and

it will be apparent that various changes 55 may be made in the form, construction and arrangement of the parts of the molds and the steps of the process without departing from the spirit and scope of the invention or sacrificing any of its material advantages, 60 the form hereinbefore described being merely a preferred embodiment thereof.

I claim:—

1. The process of casting a closet bowl, which comprises casting a part of the bowl 65 below a curved plane lying along the up-siphon passageway and at the same time separately casting a part of the bowl lying above said plane and securing the two parts together one on top of the other. 70

2. The process of casting a closet bowl, which comprises casting a part of the bowl below a plane lying along the up-siphon passageway and at the same time separately casting a part of the bowl lying above said 75 plane and securing said parts together one on top of the other.

3. The process of casting a closet bowl, which comprises casting a part of the bowl below a plane lying along the up-siphon 80 passageway and at the same time separately casting a part of the bowl lying above said plane, separately casting a siphon tongue, positioning it and securing said separately cast parts together one on top of 85 the other.

4. The process of casting a closet bowl, which comprises casting between mold surfaces a part of the bowl below a plane lying along the up-siphon passageway and at 90 the same time separately casting between mold surfaces a part of the bowl lying below said plane, removing the internal mold members and securing said parts together while in the outer mold members. 95

5. The process of constructing a closet bowl having a siphon passageway which consists in casting the bowl in sections simultaneously and subsequently securing said sections together, a pair of said sections 100 defining the substantially horizontal part of the siphon passageway between them.

Signed in the presence of two subscribing witnesses.
